ROUTING MACHINE

Thomas L. Siebenthaler, Kansas City, Mo.

Application April 23, 1934, Serial No. 721,891

2 Claims. (Cl. 90—15)

This invention relates to machines used in the printing trade for the conditioning of engraved or etched printing plates and which is adapted to plane said plates to a type-high condition and to cut away certain portions of the plates that are not desirable.

One of the primary aims of this invention is to provide a machine of the aforementioned character that will be exceptionally accurate in that it has means for positively maintaining the router bit and motor driving the same in a fixed parallel plane to the plane of the bed supporting the engraving or cut being treated.

Another object of this invention is to provide a routing and type-high machine wherein is embodied unique and novel mounting means for the motor which drives the router bit or plane, such mounting means including structure for vertically adjusting the motor and for moving the same about a plurality of pivotal points whereby quick and easy action takes place and positive secure support is afforded.

A still further primary aim of the invention is to provide a routing machine that is unusually strong, durable and rugged; will withstand hard usage, yet will perform unusually heavy work because of the peculiar type of supporting means that is embodied in the machine.

With the foregoing broad objects in mind and minor objects which will be made apparent during the course of the specification, the machine will now be described by referring to the accompanying drawing, wherein:

Figure 1 is a top plan view of the machine embodying this invention.

Fig. 2 is a front elevation of the same with the bed and rails in section.

Fig. 3 is an enlarged, detailed, side elevation of the motor and associated bracket entirely removed from the other parts of the structure.

Fig. 4 is an enlarged, fragmentary, detailed, sectional view of the adjusting means for the motor, taken on line IV—IV of Fig. 3, and,

Fig. 5 is a similar detailed view taken on line V—V of Fig. 3, the motor being left in elevation.

In constructing a device of this character, care should be taken that the castings are carefully machined because accuracy with respect to interengaging parts becomes necessary where micrometer adjustment is needed. This particular piece of equipment comprises a base 8 having a flat horizontal, planar surface 10, upon which rests the printing plate 12 that is in the form of an ordinary zinc etching or half-tone. Along each of two edges of base 8 is positioned an

upstanding support rail 14, the upper edge of which is tapered to reduce the bearing surface. At one corner of base 8 is a fixture 16 which carries standard 18 in the form of a shaft upon which is pivotally mounted one end of an arm 20 which forms one of a plurality of such arms that are pivotally interconnected as shown.

In this instance but one more arm 22 is employed and the free end of this latter arm carries a bracket 24. The means of pivotally interconnecting bracket and arm 24 and 22 respectively is a pair of outstanding ears 26, through which passes pivot shaft 28. The lower end of bracket 24 carries bar 30 which rests upon both of rails 14 as shown in Figs. 1 and 2. The lower edge of this bar 30 is, therefore, in a plane parallel to the surface 10 of base 8 because the upper edges of both rails 14 are in said plane. To use the machine for mortising, arms 20 and 22 are raised and lowered by lever 34 that is bifurcated at one end to underlie tube 33 which surrounds shaft 18 and directly engages arm 20. This lever is pivoted to bed 8 as at 35 and operation may take place by foot or hand power as desired.

A motor 32 is mounted upon bracket 24 by means of a holder 34 which directly engages and is affixed to motor 32 by suitable bolts 36. Holder 34 is formed as shown in Fig. 5 and a dovetailed slot 38 is formed in bracket 24 to slidably receive holder 34. Thus motor 32 is mounted for vertical rectilinear reciprocating movement toward and from base 8. The pivotal connection at 28 is eccentric to the axis of motor 32 which allows easy manipulation and freedom when the machine is being used.

To move motor 32 and hold it in a desired position, there is provided an adjusting screw 40 which passes through an overhanging part 42 of bracket 24 and a collar 44 assists in maintaining the adjusting screw in operative relation. Screw 40 is in screwthreaded engagement with the socket 46 formed in holder 34 so that upon turning said screw 40 the holder and motor 34 and 32 respectively will be moved. A router bit or any other suitable tool 48 is carried by chuck 50 and rotated by said motor. This tool 48 is adjustable toward and from base 8 and in a line transversely to bar 30.

In operating the machine, the ends of bar 30 are grasped and tool 48 drawn across or positioned upon cut 12 wherever desired. In so constructing this machine, arms 20 and 22 are relieved of weight and become merely support guides while all of the weight and support neces-

sary is located directly at the work through the medium of bar 30 and the supporting rails 14.

But one form of the construction contemplated by this invention is illustrated and described and it is understood that modifications falling within the spirit of the invention might be employed without departing from the scope of the appended claims.

Having thus described the invention, what is claimed as new and desired to be secured by Letters Patent is:

1. A routing machine of the kind described, comprising, a base; a plurality of rails on the base having upper edges in a common plane parallel to the plane of said base; a standard at one corner of said base; a plurality of pivotally interconnected arms mounted on said standard for movement thereabout; a bracket pivotally carried by the outermost arm; a motor mounted for

vertical rectilinear movement on the said bracket; means for moving and holding said motor in the adjusted position; a bar on the bracket slidably resting on the upper edges of said rails; and a router bit carried by the motor longitudinally movable independently of the motor transversely of the said bar toward and from the said base. 5

2. A machine of the character described comprising a base; a standard carried by the base; a plurality of pivotally interconnected arms 10 mounted on the standard; a motor carried at the free end of one of said arms, said standard comprising a vertical shaft and a tube surrounding said shaft, the said arms being directly connected to said tube for rotary and longitudinal movement relative to the shaft; and a lever pivotally mounted on the base for moving said tube and associated arms vertically along the shaft. 15
